UNITED STATES PATENT OFFICE.

BENJAMIN S. CASTLE, OF JOHNSTOWN, OHIO.

IMPROVEMENT IN SAW-SETS.

Specification forming part of Letters Patent No. **143,272**, dated September 30, 1873; application filed June 21, 1873.

To all whom it may concern:

Be it known that I, BENJAMIN S. CASTLE, of Johnstown, in the county of Licking and State of Ohio, have invented a new and Improved Apparatus for Setting Saws; and I do hereby declare that the following is a full, clear, and exact description of the same, reference being had to the accompanying drawing forming a part of this specification, in which—

Figure 1 is a longitudinal sectional elevation, and Fig. 2 a plan view.

The invention will first be fully described and then pointed out in the claim.

A is a bench, in a groove of which I arrange a setting-plate, D, over which I have a setting-clamp, E, and setting-tool F. The clamp E consists of a strong bar extending over the setting-plate nearly its whole length,

then binding horizontally beyond the edge, and then down through the frame to the levers G, which are forced down by a screw, H, to press the clamp down on the saw, which is laid on the plate D. The levers are forced up by a spring, I. The tool is forced down on the saw-teeth by the blows of a hammer, and it is forced up by a spring, M.

Having thus described my invention, what I claim as new, and desire to secure by Letters Patent, is—

The clamp E, levers G, screw H, and spring I, combined with the setting-plate, substantially as specified.

BENJAMIN S. CASTLE.
